FLUID TRANSFER APPARATUS

Warner T. Tabb, Brooklyn, N. Y., assignor, by
mesne assignments, to Reconstruction Finance
Corporation, New York, N. Y., a corporation of
the United States

Application October 22, 1940, Serial No. 362,179

17 Claims. (Cl. 103—150)

The present invention relates to fluid transfer apparatus and more particularly to pump apparatus adapted to effect transfer of fluids either liquid or gaseous for a variety of purposes.

General objects of the invention are the provisions of such apparatus which is of simple and economical construction with minimization of leakage tendencies, requires little if any careful and costly machining and treating of cooperating parts frictional engagement between which is relatively minimized thus reducing tendency of wear which might eventually require replacements or repair, can be readily and easily assembled and disassembled, is efficient in operation to transfer fluid effectively at a relatively uniform rate with surging and pulsation of pumped medium reduced to a minimum, and is capable of efficient high frequency operation; and structural embodiments of such apparatus which can readily and economically be made and assembled in mass production while assuring efficient use and operation thereof.

More specific objects of the invention are the provision of such apparatus characterized by a pump chamber formed by cooperation of a casting and a diaphragm having lateral rigidity and certain spring characteristics with diaphragm biasing leaf-like spring structure having certain spring characteristics mounted in the chamber in a manner to provide certain net spring characteristics for combined diaphragm and spring construction; and to provide such apparatus wherein the mounting and characteristics of said diaphragm structure are such that an outwardly projecting diaphragm operating member mounted on the diaphragm is properly and efficiently guided in its operation without necessitating use therefor of bearing supports or like guiding means which might tend to introduce undesirable problems of construction, manufacture and wear; and which assure efficient operation of said apparatus by mechanical means that may tend in operation to flex said diaphragm only inwardly.

Another object of the invention is the provision in such apparatus of suitable fluid passages past a diaphragm biasing spring disc structure within the pump chamber of such a diaphragm pump, either through the diaphragm or around the periphery thereof, which assures efficient use and operation thereof.

A further object of the invention is to provide such diaphragm pump structure which, though adapted to effect operation when mounted in a position other than with the diaphragm thereof

substantially horizontal and the pump chamber thereabove which may be termed the "vertical pump position," it is particularly effective for continuous efficient operation when mounted in such vertical pump position, the casing structure defining at least a portion of the pump chamber, the inlet and outlet passages communicating therewith and valves structures in the passages being such and cooperating in a manner as to assure effective escape of indrawn relatively light foreign fluid, such as air or gaseous liquid when a liquid, e. g. hydrocarbon fuel, is being transferred by the pump.

A still further object of the invention is to provide such diaphragm pump apparatus of such construction as to permit easy and economical provision of simple and effective priming means, manually operable if desired, which requires no particular provision of packing to prevent leakage, which can be simply mounted and demounted without affecting assembly of other parts, and which can be manipulated effectively to discontinue transfer operation of the pump apparatus without disturbing mechanical means effecting such transfer operation.

An additional object of the invention is the provision of such diaphragm pump apparatus characterized by effective provision in the inlet and/or outlet passages of simplified pulsation eliminating means whereby surging of and pulsations in supplied and/or delivered fluid, such as liquid fuel, is effectively minimized assuring efficient and relatively uniform supply and/or delivery thereof.

Other objects of the invention will in part be obvious and will in part appear hereinafter.

The invention accordingly comprises the features of construction, combination of elements and arrangement of parts, which will be exemplified in the construction hereinafter set forth and the scope of the invention will be indicated in the claims.

For a fuller understanding of the nature and objects of the invention, reference should be had to the following detailed description taken in connection with the accompanying drawing, in which:

Fig. 1 is a top plan view of one embodiment of the apparatus of the present invention;

Fig. 2 is a sectional view taken on line 2—2 of Fig. 1;

Fig. 3 is a top plan view of the structure shown in Figs. 1 and 2 but with parts removed and broken away; and

Fig. 4 is a sectional view taken on line 4—4 of Fig. 1.

Various diaphragm pump structures have been proposed for use in transferring fluids, both gaseous and liquid. For example, such structures have been proposed for use in both mechanical and electrical gasoline injection systems as well as for use in fuel supply systems of internal combustion engines of the Diesel type, oil burners and the like. Many of such structures, however, have been of such construction as to require extremely careful and costly machining and fitting of parts, treating of material to harden frictionally engaging parts, and costly and frequently inefficient provisions of packing to prevent leakage; and have been complicated making assembly and disassembly difficult, subject to wear of frictionally engaging parts making repair or replacement of parts eventually necessary, and inefficient and non-uniform in operation. Further, such structures have been such as to make their use in systems requiring high speed operation, for example fuel supply systems for internal combustion engines, extremely uncertain and unsuitable.

These and other difficulties are efficiently alleviated by the apparatus of the present invention which has been found to be highly satisfactory for use, by way of example, in fuel supply systems for Diesel engines. The diaphragm pump structure of the invention has no working parts characterized by frictional engagement of guiding bearings, other than a roller, if desired, used as a cam follower to impart movement to a diaphragm operating member or rod. The diaphragm operating member is preferably anchored to the diaphragm to project outwardly therefrom free from any bearing support. It is guided in its operation solely by the diaphragm having lateral rigidity mounted with peripheral portions thereof seated on a casing cooperating with the former to form a chamber. A leaf-like spring structure is mounted in the chamber with outer portions thereof rigidly supported by the casing and forms a biasing abutment for the central portion of the diaphragm structure to obtain the desired biasing action. The diaphragm structure has certain spring characteristics as does the spring structure and these are so correlated as to give net spring characteristics for the combined spring and diaphragm structures as to make for desired action.

Such spring structure may be in the form of one or more laminae of sheet metallic material of any suitable configuration such as a hub portion with two or more radiating arms but preferably comprises one or more discs of spring steel or the like, preferably cup-shaped. When such discs are used provision is made for passage of fluid therewith by any suitable means such as apertures or cut-outs therein but preferably by providing in the casing a series of spaced apart seats around the circumference thereof with intermediate passage spaces.

The diaphragm structure preferably comprising one or more discs of steel or other resilient metallic material having desired lateral rigidity may be assembled on or anchored to the operating member in any suitable manner but preferably is centrally apertured to receive the inner end of the operating member or rod which projects therethrough to receive a nut or collar.

The central portion of the spring structure, to form a biasing abutment for the diaphragm structure, may be secured centrally to the dia-

phragm structure in any suitable manner and have lateral clearance with its supporting means but for simplicity of manufacture and assembly it is preferred to provide a central hole in the spring structure which receives with clearance the projecting end of the operating rod or the nut or collar anchoring the latter in position.

Inlet and outlet passages having valves therein are provided in the casing to communicate with the pump chamber. The apparatus may be used efficiently in a variety of positions but preferably is mounted vertically with the passages communicating with the chamber through the top of the casing and the valves therein positioned angularly with respect to each other. The portions of the seats of said valves, preferably of the check valve type, nearest each other are at highest elevation with that of the outlet valve above that of the inlet valve. This permits effective escape at each pump cycle of indrawn relatively light foreign fluid, such as air and gaseous fuel, when liquid fuel is being transferred, whereby tendency to build up in the pump chamber a body of such foreign fluid or gaseous matter that might eventually prevent efficient operation of the pump is eliminated.

Provision is made for manually or otherwise priming the apparatus. This is accomplished by means exterior of the chamber whereby necessary for packing and tendency of leakage are eliminated. Suitable mechanism permits raising or moving inwardly the diaphragm operating member. Preferably a member or shaft is rotatably mounted on the apparatus exteriorly of the chamber preferably on a base member supporting the diaphragm and casing. The inner end thereof may be provided with a cam or the like or so shaped as to engage means such as a shoulder on the operating rod to impart to the latter the desired movement when the priming member or shaft is rotated. When operating the apparatus by a cam with the outer end of the operating rod biased to the external surface thereof to act as a cam follower the priming mechanism may be utilized to arrest fluid transfer operation of the apparatus merely by rotating the shaft and holding it in rotated position to raise the cam follower free from the cam and hold it in raised position.

When the apparatus is used for transferring liquid it is desirable to eliminate pulsations or surges in delivered fluid and/or in liquid being supplied to the diaphragm pump. Pulsations or surges in delivered liquid might interfere with required degree of uniformity of feed and similar pulsations in the supply might interfere with efficient operation of the transfer pump. Should the pump be operated at times when pulsations were building up pressure in the supply to the pump and at other times when pulsations were reducing the pressure the transfer operation of the pump might well vary, affecting delivery of fluid undesirably. Pulsations are effectively eliminated by the apparatus with the provision of means each comprising a flexible diaphragm backed by a body of trapped gas forming a portion of the wall of the fluid passage near the valve in the passage. As pointed out previously such provision may be made in either or both the inlet and outlet passages.

Referring to the drawings like numerals refer to like parts throughout. A base member or plate 10 is provided with an annular seat 11 upon which seats the periphery of a diaphragm 12. The diaphragm 12 may comprise one or more

laminae of sheet steel and preferably has a gasket ring 13 located on either side of the periphery thereof. A casing 14 of general cup-shape and preferably domed at the top has an annular seating surface 15 adapted to cooperate with the seat 11 on the base 10 to clamp the diaphragm 12 and gaskets 13, 13 therebetween in a fluid-tight manner, suitable screws 16-16 being used to clamp the parts together.

An operating member or a rod 17 is anchored centrally to the diaphragm 12 to project outwardly therefrom. This member preferably comprises a fork 18 between the legs of which is rotatably mounted a roller 19 constituting a cam follower adapted to ride on the outer surface of a cam 20. A flange 21 at the base of the operating member 17 provides a bearing shoulder for a central portion of the diaphragm 12 and an inner stud end 22 thereof projects through a central aperture in the diaphragm 12 and is externally threaded to receive a nut 23 between which and the flange 21 is clamped the diaphragm structure with an interposed washer 24 and suitable gasket rings 25, 25.

The base member 10 is provided centrally with a hole 26 larger than the operating rod 17 and the roller 19 carried thereby to permit without contact free reciprocation of the latter therethrough.

The diaphragm 12 and the casing 14 cooperate to provide a pump chamber 27 on the side walls of which are formed a plurality of circumferentially spaced seats 28-28 providing a plurality of intermediate fluid passages 29-29 past the seats 28-28. A diaphragm biasing leaf-like spring structure 30, preferably formed of one or more laminae of sheet steel of disc configuration is mounted in the chamber 27 with its periphery supported on the seats 28-28 preferably with at least small lateral clearance. This spring structure 30 is provided with a central aperture 31 which engages over the inner end 22 of the operating rod and the structure mounted thereon preferably receiving the nut 23 with at least small lateral clearance at points of greatest lateral dimension with the portions adjacent the aperture bearing against the washer 24 to form a biasing abutment for the diaphragm structure.

This spring structure 30 may be cupped and positioned as shown in the drawings. Obviously the position of the spring structure 30 may be reversed provided the seats 28-28 and the diaphragm structure or anchorage structure of the operating rod are suitably altered to accommodate such reversal. The position and shape of the spring structure will be largely dictated by the results desired, the dimensions such as relation of thickness of spring structure to diameter, degree of initial cupping, etc. For some purposes substantially flat disc spring structure may be desirable, such as where the diaphragm is to be flexed in opposite directions from an intermediate neutral position which may be determined by a substantially flat diaphragm in the assembly when not stressed. Equalization of such travel results in the least strain on the diaphragm. The use of a flat spring structure assures compactness of pump construction.

A flat or initially uncupped diaphragm, such as that shown by way of example in the drawings, has certain well defined characteristics as a spring in and of itself. These are such as may tend to result in excessive pressure of the cam follower against the cam in the positions of maxi-

mum flexure of the diaphragm, such as the innermost position of the diaphragm and associated parts of the structure shown in the drawings. Further in such a structure those characteristics 5 may tend to prevent the cam follower from effectively following the cam in the outermost position of the diaphragm. The plotted curve of those diaphragm characteristics is found to be of great curvature indicating that the rate of change 10 of positive and negative pressures may be of an objectionable degree under certain conditions making it advisable to use very small diaphragm deflections.

This may be compensated for or effectively corrected by the use of an initially cupped spring 15 which has a reverse spring characteristic curve. Net spring characteristics of the combination of such diaphragm and spring structure can thus be obtained which will assure approximately uniform pressure of the cam follower on the cam. Even a less pressure in the innermost position 20 of the diaphragm than in the neutral or outermost positions thereof, or greater pressure in the latter position than when in the neutral position, may be attained by proper predetermined combinations. Thus the spring rigging of the present pump construction while making for simple and compact pump construction assures long life for the diaphragm and its operating 25 mechanism and efficient pump performance with the use of diaphragm and biasing spring structure of simple design.

The casing 14 is provided with a pair of opposed bosses 32 and 33 having respectively internally threaded recesses 34 and 35 to receive 30 fluid supply and delivery conduits. The recess 34 communicates through the passage 36 with a fluid passage chamber 37 closed at the top by a removable cap 38 on the inlet side and a similar passage 39 communicates with a similar chamber 40 closed by a similar cap 41 on the outlet side. The chambers 37 and 40 constitute the inner ends of the inlet and outlet fluid passages 35 communicating with the pump chamber 27 through suitable valve structure located therein. These valves 40 preferably are of the check valve type so mounted in their respective chambers 40 as to permit fluid to flow into the pump chamber 27 from the inlet side and fluid to flow out of the pump chamber on the outlet side, as indicated in the drawings.

The check valve 42 in the inlet chamber 37, as is more fully described in my copending application Serial No. 362,180 filed October 22, 1940, comprises a sleeve-like cage 43 having a seat 44 formed thereon against which is biased a valve plate 45 by a leaf-like spring structure 46 centrally apertured to receive a stud structure 47 preferably anchored to the valve plate 45, with spacing means 48 interposed between the valve plate structure 45 and the spring structure 46 to form opposed abutments whereby the valve plate can be biased to its seat and the parts of the valve assembled in the cage 43 by a splitting ring 49 seated within a groove in the cage 43 and bearing against peripheral portions of the spring structure 46. The base of the cage 43 is machined out at 50 to form a tapered throat for the valve port.

The check valve in the outlet chamber 40 is similar in construction to the check valve in the inlet chamber 37 except perhaps in one particular. The check valve on the inlet side is preferably provided with a hole 51 through the cage 43 which communicates with the annular recess

adjacent to and surrounding the valve seat on the chamber side thereof at substantially its highest point as shown. Such a hole having no purpose in the check valve or the outlet passage may be omitted. In the crown of the domed chamber wall adjacent the tapered throat 50 of the outlet valve cage 43 at its point of highest elevation is machined a way 52 to cooperate with the surface of the throat 50 of the outlet valve, the upwardly inclined inner surface of the pump chamber 27 and the hole 51, to provide an escape way for relatively light foreign fluid that may be drawn into the pump chamber with the fluid being transferred, for example, air and fuel fumes, when hydrocarbon fuel is being transferred. This will prevent undue accumulation of gaseous medium in the transfer pump chamber which might tend to affect efficient operation thereof and possibly prevent in the ultimate any transfer of fluid.

Pulsation eliminators are provided in the inlet and outlet passages by forming recesses 53, 53 in the caps 38 and 41 and trapping a body of air therein by flexible diaphragms 54, 54 of resilient material, such as neoprene, each held in position on an annular seat 55 by a press-fitted ring 56.

For purposes of moving the operating rod 17 axially for hand priming or the like a shoulder 57 is provided thereon by forming a hole 58 through one leg of the roller fork. A radially extending boss 59 on the base 10 is bored to receive rotatably a shaft 60 having a circumferential groove 61 in which the end of a pin or set screw 62 seats to hold the shaft in position. The inner end 63 of the shaft 60 is machined off on the top side thereof to form a pair of camming portions 64, 64 one of which is adapted to bear against the shoulder 57 when the shaft 60 is rotated in a clockwise or counter-clockwise direction thereby to lift the operating rod and flex the diaphragm inwardly against the biasing spring so as to raise the cam roller 19 from the cam 20. An operating arm 65 is keyed to the shaft 60 for rotating it and a coil spring 66 around the end of the shaft 60 having one end thereof anchored to the base member 10 and the other end thereof anchored to the arm 65 assures return of the arm 65 to a disengage position determined by a stud 67 bearing against the edge of the casing 14.

By way of example the transfer pump of the present invention may be mounted by means of mounting ears 68-68 on the base member 10 upon the case of a high pressure injecting apparatus for feeding fuel to a Diesel engine. Such injecting apparatus may comprise a plurality of high pressure injecting pump devices, one for each cylinder of the engine, all operated by a common cam. The circumferential surface of this cam may be provided with lobes equal in number to the number of high pressure injecting devices so that each revolution of the cam, such as 20, will result in a number of complete transfer pump cycles equal to the number of high pressure injecting devices each of which is operated during one cam revolution. Such operation obviously will be of very high frequency and it has been found that the apparatus of the present invention with the provision of diaphragm travel of about .0125" on each side of the neutral position will perform its functions under such conditions in a highly satisfactory manner. It will further be noted that with such a mounting of

the device all of the parts thereof can easily and readily be assembled from the top.

In operation when the operating rod is lifted upwardly by a cam the resultant inward flexing of the diaphragm against the biasing action of the spring structure minimizes the space of the pump chamber and when the cam permits the operating rod to be moved outwardly by the biasing spring structure partial vacuum is created in the pump chamber producing a differential in pressure on opposite sides of the inlet valve sufficient to open the same and cause fluid to flow into the pump chamber. When the operating rod is again moved inwardly the inlet valve automatically closes, and pressure built up in the pump chamber by inward flexing of the diaphragm causes the outlet valve to unseat and fluid to be delivered through the outlet passage from the pump chamber. When the biasing spring structure is again permitted to move the diaphragm outwardly the outlet valve automatically closes and the cycle is then repeated. The pulsation eliminator diaphragms 54, 54, having bodies of compressible fluid, such as air trapped therebehind, and forming walls of the inlet and outlet passages, effectively damp pulsations in the supplied and delivered liquid, which pulsations as is well known tend to occur in such systems through operation of transfer pumps and check valves thereof. The pump apparatus may be manually primed by flexing the diaphragm inwardly and outwardly a number of times, which can be accomplished by pulling on the priming arm, releasing it and repeating the operation. Operation of the transfer pump may be arrested by pulling on the priming arm and holding it.

It will be understood that the transfer pump structure of the invention is not limited to the use of a flat or initially uncupped diaphragm. Obviously an initially cupped diaphragm could be used when desired, the associated structures being altered in shape and/or dimensions suitably to accommodate the same, or one might use diaphragms of other configurations, such as corrugated, etc., when the inherent characteristics thereof contribute certain desired action. Of course such diaphragms also have definite spring characteristics and that which is set forth above as to net spring characteristics of combined diaphragm and spring constructions is generally applicable to constructions including cupped or corrugated diaphragms, and the like.

The outer edge of the diaphragm may be rigidly clamped in mounted position, or may be resiliently supported to a certain extent by the use of gaskets such as 13, 13 if formed from resilient material provided the clamping force is not so great as entirely to eliminate such feature. With the spring structure constructed and mounted as disclosed where at least small clearance is provided between the casing and outer edge of the spring structure and/or between the edge of spring structure at the central aperture and structure on the diaphragm received therein it will be understood there may be some guiding action of the diaphragm flexing mechanism under certain conditions of operation.

It will thus be seen that the objects set forth above are efficiently attained by apparatus of the present invention and since certain changes may be made in the above construction and different embodiments of the invention could be made without departing from the scope thereof, it is intended that all matter contained in the above description or shown in the accompanying draw-

ings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention what I claim as new and desire to secure by Letters Patent, is:

1. Fluid transfer apparatus comprising, in combination, a casing, a resilient diaphragm structure having lateral rigidity and certain spring characteristics peripherally mounted on said casing to form therewith a pump chamber, an outwardly projecting operating member rigidly mounted on said diaphragm by attachment thereto for substantial alignment of said member free from any bearing support, a diaphragm-biasing leaf-like spring structure having certain spring characteristics positioned in the chamber with outer portions thereof seated on said casing and the central portion thereof forming an abutment for said diaphragm structure, and means between substantially the central portions of said spring structure and said diaphragm structure to cause them to operate together to attain certain net spring characteristics.

2. Fluid transfer apparatus comprising, in combination, a casing, a resilient diaphragm having lateral rigidity and certain spring characteristics peripherally mounted on said casing to form therewith a pump chamber, an outwardly projecting operating member rigidly mounted on said diaphragm free from any bearing support, means secured to said diaphragm projecting on the chamber side thereof, and diaphragm-biasing spring disc structure having peripheral portions thereof seated on the casing within the chamber and its central portion engaging said projecting means in a manner to cause said structures to operate together to attain certain net spring characteristics.

3. Fluid transfer apparatus comprising, in combination, a cupped casing, a resilient diaphragm having lateral rigidity and certain spring characteristics peripherally mounted on said casing to form therewith a pump chamber, operating means rigidly anchored to said diaphragm to form a member projecting into the chamber and an operating rod extending outwardly from said diaphragm free from any bearing support, and a diaphragm-biasing spring disc structure having peripheral portions thereof seated on the casing within the chamber and its central portion engaging said projecting member in a manner to cause said structures to operate together to attain certain net spring characteristics.

4. Fluid transfer apparatus comprising, in combination, a cupped casing, a resilient diaphragm having lateral rigidity and certain spring characteristics peripherally mounted on said casing to form therewith a pump chamber, operating means rigidly anchored to said diaphragm to form a member projecting into the chamber and an operating rod extending outwardly from said diaphragm free from any bearing support, and a diaphragm-biasing spring disc structure having its periphery seated on the casing within the chamber at spaced apart points to form intermediate fluid passages and its central portion engaging said projecting member in a manner to cause said structures to operate together to attain certain net spring characteristics.

5. Fluid transfer apparatus comprising, in

combination, a cupped casing, a resilient diaphragm having lateral rigidity and certain spring characteristics peripherally mounted on said casing to form therewith a pump chamber, an operating rod rigidly anchored centrally to said diaphragm with the inner end thereof extending through the diaphragm into the chamber and the outer end thereof extending from said diaphragm free from any bearing support, and a cupped spring disc structure having its periphery seated on the casing within the chamber at spaced apart points to form intermediate fluid passages, said spring structure biasing said diaphragm with the inner end of said rod engaging the central portion of said disc structure in a manner to cause said structures to operate together to attain certain net spring characteristics.

6. Fluid transfer apparatus comprising, in combination, a cupped casing, a resilient metal diaphragm having lateral rigidity and certain spring characteristics peripherally mounted on said casing to form therewith a pump chamber, inlet and outlet valves communicating with the chamber, an operating rod rigidly anchored centrally to said diaphragm in such manner as to form a projection on the chamber side thereof, said rod extending outwardly from said diaphragm free from any bearing support and terminating in a cam follower, a plurality of circumferentially spaced seats inside the chamber, and a cupped spring disc structure peripherally supported on said seats with its diameter less than the internal diameter of the chamber to provide fluid passages intermediate said seats, said spring structure biasing said diaphragm with said projection engaging the central portion of said disc structure in a manner to cause said structures to operate together to attain certain net spring characteristics.

7. In fluid transfer apparatus, the combination comprising a resilient diaphragm structure having certain spring characteristics peripherally mounted for laterally inward movement of outer portions thereof during flexure, means to flex said diaphragm, a diaphragm-biasing leaf-like spring structure having certain different spring characteristics mounted with outer portions thereof supported, and thrust means between substantially the central portions of said diaphragm and spring structures causing them to operate together to attain certain net spring characteristics of the assembly making for desired action.

8. In fluid transfer apparatus, the combination comprising a resilient diaphragm structure having certain spring characteristics peripherally mounted for laterally inward movement of outer portions thereof during flexure, means to flex said diaphragm, a diaphragm-biasing leaf-like spring structure having certain spring characteristics substantially the reverse of those of said diaphragm structure mounted with outer portions thereof supported, and thrust means between substantially the central portions of said diaphragm and spring structures causing them to operate together so that the spring characteristics of the latter will compensate for those of the former to attain certain net spring characteristics of the assembly making for desired action.

9. Fluid transfer apparatus comprising, in combination, a casing, a resilient diaphragm structure having lateral rigidity and outer edges thereof mounted on said casing to form a pump chamber, an outwardly projecting operating cam follower member rigidly mounted on said

diaphragm structure by attachment thereto for substantial alignment of said member free from any bearing support, and a diaphragm biasing spring structure positioned in the chamber with outer portions thereof seated on said casing and a central portion thereof forming an abutment for said diaphragm structure.

10. Fluid transfer apparatus comprising, in combination, a casing, a resilient diaphragm structure having lateral rigidity peripherally mounted on said casing to form therewith a pump chamber, an outwardly projecting operating member mounted on said diaphragm by attachment thereto for substantial alignment of said member free from any bearing support, a diaphragm-biasing leaf-like spring structure positioned in the chamber with outer portions thereof seated on said casing, and a thrust element between substantially the central portions of said spring and diaphragm structures to cause the former to bias the latter.

11. Fluid transfer apparatus comprising, in combination, a cupped casing, a resilient metal centrally apertured diaphragm having lateral rigidity and certain spring characteristics resiliently mounted at its periphery on said casing in a substantially fluid-tight manner to form therewith a pump chamber, inlet and outlet valves communicating with the chamber, an operating rod extending through the aperture in said diaphragm and anchored thereto by resilient gasket means with one end comprising projecting means in the chamber and the other end extending outwardly from said diaphragm free from any bearing support and comprising operating means, and a leaf-like spring structure comprising a washer-like spring member having outer portions thereof supported on said casing and of a diameter less than the internal diameter of the chamber, said spring structure biasing said diaphragm with said projecting means engaged in the central aperture of said washer-like spring member with the greatest transverse dimension of said projecting means being less than the diameter of the spring aperture.

12. Fluid transfer apparatus comprising, in combination, a cupped casing, a resilient metal centrally apertured diaphragm having lateral rigidity and certain spring characteristics resiliently mounted at its periphery on said casing in a substantially fluid-tight manner by resilient gasket means to form therewith a pump chamber, inlet and outlet valves communicating with the chamber, an operating rod extending through the aperture in said diaphragm and anchored thereto by resilient gasket means with one end comprising projecting means in the chamber and the other end extending outwardly from said diaphragm free from any bearing support and comprising operating means, a plurality of circumferentially spaced seats inside the chamber, and a leaf-like spring structure comprising a washer-like spring member having outer portions thereof supported on said seats and of a diameter less than the internal diameter of the chamber to provide fluid passages intermediate said seats, said spring structure biasing said diaphragm with said projecting means engaged in the central aperture of said washer-like spring member with the greatest transverse dimension of said projecting means being less than the diameter of the spring aperture.

13. Fluid transfer apparatus comprising, in combination, a casing, a resilient initially substantially flat diaphragm structure having lat-

eral rigidity and certain spring characteristics with outer edges thereof mounted on said casing for laterally inward movement of outer portions of said diaphragm structure during flexure thereof and to form with said casing a pump chamber, means to flex said diaphragm, and a diaphragm-biasing leaf-like spring structure comprising a cupped washer-like spring member having certain spring characteristics substantially the reverse of those of said diaphragm structure mounted with outer portions thereof supported on said casing, said spring structure being arranged in the chamber with the cupping thereof facing away from said diaphragm and the central portion of the former biasing the latter so that the spring characteristics of the former compensate for those of the latter to attain certain net spring characteristics and assure approximately uniform pressure on the diaphragm flexing means throughout operative cycles.

14. Fluid transfer apparatus comprising, in combination, a casing, a resilient initially substantially flat diaphragm structure having lateral rigidity and certain spring characteristics with outer edges thereof mounted on said casing to form a pump chamber, means to flex said diaphragm, a diaphragm-biasing leaf-like spring structure comprising a washer-like spring member having a substantially centrally located aperture and certain spring characteristics substantially the reverse of those of said diaphragm structure mounted with outer portions thereof supported on said casing, and thrust means between substantially the central portion of said diaphragm structure and said spring structure having a portion projecting into the aperture in said spring member causing them to operate together so that the spring characteristics of the latter compensate for those of the former to attain certain net spring characteristics and assure approximately uniform pressure on the diaphragm flexing means throughout operative cycles.

15. Fluid transfer apparatus comprising, in combination, a casing, a resilient initially substantially flat diaphragm structure having lateral rigidity and certain spring characteristics with outer edges thereof mounted on said casing to form a pump chamber, means to flex said diaphragm, a diaphragm-biasing leaf-like spring structure comprising a washer-like spring member having a substantially centrally located aperture and certain spring characteristics substantially the reverse of those of said diaphragm structure mounted with outer portions thereof supported on said casing, and thrust means between substantially the central portion of said diaphragm structure and said spring structure having a portion projecting into the aperture in said spring member causing them to operate together so that the spring characteristics of the latter compensate for those of the former to attain certain net spring characteristics and assure approximately uniform pressure on the diaphragm flexing means throughout operative cycles, said spring member being of a diameter less than the internal diameter of the chamber and the greatest transverse dimension of said projecting portion being less than the diameter of the spring aperture.

16. Fluid transfer apparatus comprising, in combination, a casing, a centrally apertured resiliently initially substantially flat diaphragm structure having lateral rigidity and certain spring characteristics with outer edges thereof

resiliently mounted on said casing in a substantially fluid-tight manner by resilient gasket means to form a pump chamber, means to flex said diaphragm, and a diaphragm-biasing leaf-like spring structure comprising a cupped washer-like spring member having certain spring characteristics substantially the reverse of those of said diaphragm structure mounted with outer portions thereof supported on said casing, said spring structure being arranged in the chamber with the cupping thereof facing away from said diaphragm and the central portion of the former biasing the latter so that the spring characteristics of the former compensate for those of the latter to attain certain net spring characteristics and assure approximately uniform pressure on the diaphragm flexing means throughout operative cycles.

17. Fluid transfer apparatus comprising, in combination, a casing, a centrally apertured resilient initially substantially flat diaphragm structure having lateral rigidity and certain

spring characteristics with outer edges thereof resiliently mounted on said casing in a substantially fluid-tight manner by resilient gasket means to form a pump chamber, thrust means 5 anchored in the aperture in said diaphragm by resilient gasket means and projecting into the chamber, means to flex said diaphragm, and a diaphragm-biasing leaf-like spring structure comprising a washer-like spring member having certain spring characteristics substantially the reverse of those of said diaphragm structure mounted with outer portions thereof supported on said casing and having said thrust means received in the aperture therein causing said diaphragm structure and said spring structure to 10 operate together so that the spring characteristics of the latter compensate for those of the former to attain certain net spring characteristics and assure approximately uniform pressure 15 on the diaphragm flexing means throughout operative cycles.

WARNER T. TABB.
